UNITED STATES PATENT OFFICE

ISRAEL EVANS, OF SAN BERNARDINO, CALIFORNIA.

METAL-FACED TILE.

Application filed March 16, 1927. Serial No. 175,720.

My invention is a metal faced tile constructed with a hardened plastic back with a metal face or surface.

An object of my invention is the construction of a tile having a metal face and a hardened moldable plastic composition forming the back. The tile may be used for interior purposes for decoration or wall covering, or it may be constructed as a roof covering. The tile is preferably made with a noncorrodible facing, such as copper.

Another object of my invention is to construct a tile having a metal face, the face having lugs or the like soldered or welded thereon, such lugs becoming embedded in the moldable plastic composition.

In constructing my tile for use in surface walls, mantels, or the like, I preferably use thin sheet metal with angular or channel shaped lugs soldered or welded on the back of the metal face. These are set in from the corners and become embedded in the plastic composition, which may be cement molded with sand or the like. For wall surfacing the edges of the metal are preferably turned inwardly to give a finished effect of a slightly rounded edge.

For forming roof tiles, these are preferably made with a sheet metal facing, the tiles being formed with a tongue on one side edge and with a groove formed by bending the metal on the other, to form tongue and groove joints running from the eaves of a roof upwardly. The metal is shaped to fit on the upper part of a tile underneath the tile next above and having a projecting end extending over the surface of the tile next below, in order to form a water tight joint and shed the water.

My invention is illustrated in its various aspects in the following drawings, in which:

Figure 1 is a cross section through a facing tile.

Figure 2 is a perspective view of a single tile.

Figure 3 is a face view of a section of a wall constructed with facing tile.

Figure 4 is a section through a wall on the line 4—4 of Fig. 3.

Figure 5 is a top view of a roof showing my metal faced roofing tiles.

Figure 6 is a perspective view of one of the roofing tiles viewed from the groove side.

Figure 7 is a longitudinal section through a roof on the line 7—7 of Fig. 5.

Figure 8 is a transverse section of a roof

on the line 8—8 of Fig. 5 showing the manner of running off the water.

Figure 9 is a cross section of roofing tiles using an interlocking strip.

The facing tile of Figs. 1 through 4 is constructed substantially as follows:

A metal face 1, which may be formed of any shape and is illustrated as being square, has slightly inwardly turned edges 2, these being pressed at the corners 3 to form even corners without any fold. A series of lugs 4, which are shown as small channel shaped pieces of metal, are soldered or welded to the under surface of the metal facing. These lugs are preferably set inwardly from the corners, as illustrated in Figs. 1 and 3, and for a square tile usually 4 lugs are sufficient. The backing 5 of each tile is composed preferably of some moldable composition, such as cement with sand, or a fine grade of concrete, or other similar material. This plastic composition embeds the lugs and follows the curved or molded edges 2 and the corners 3 of the metal facing. It is manifest that the tiles may be made any desired thickness and it is not necessary that the lugs 4 extend to the rear surface.

For facing the tiles on a wall the procedure is substantially the same as for facing a wall with any similar tiles and in Figs. 3 and 4 a wall is indicated by the numeral 6, having a thin coating of cement 7 or the like spread thereon and the tiles being placed against this coating and a suitable mortar 8 binds the tiles on their edges one to the other. It will thus be seen that a wall facing may be built up in this manner having a metal face with composition backs for tiles, the whole being supported on a wall or the like.

The roof tile is preferably constructed substantially as follows:

This has a sheet metal facing 10 which has lugs 11 soldered or welded on the backs, such lugs being cast or molded in plastic composition 12. One side edge of the metal facing extends beyond the edge of the composition slightly forming a tongue 13 and on the other edge there is a groove 14 formed, this groove having a double bend 15 and a flange 16 positioned slightly above the main surface 10 of the sheet 10 in order to engage the tongue 13. The top of the tile is formed by an angular bend 17 in which there is a part 18 of the sheet at right angles to the surface 10 and forming an edge on the upper part of the

composition and a flange 19 parallel to the surface 10 and extending upwardly of the tile. This has nail holes 20 therethrough so that it may be nailed to roof sheathing indicated 5 by the numeral 21. The lower edge of the tile has an extension 22 of the surface metal to overlap a tile next below, as indicated in Fig. 8. The composition has a cut out section 23 at its upper and lower edge to accommodate the flange 19, as illustrated in Fig. 8, and it will be noted by this figure that in each tile the composition is slightly thicker near the lower edge than near the upper edge, this being the thickness of the metal. The tongues 10 and grooves on the side edges fit together, as shown in Fig. 7. It will thus be seen that the water flowing down the roof, which would be in a direction from right to left of Fig. 8, will be shed from one tile to the other and 15 affords no opportunity of seeping back underneath the tiles.

From the above description it will be seen that I have developed a metal faced tile which is suitable for surfacing or finishing a wall 25 and that I have also developed a type of tile suitable for roofing construction and moreover that the roofing tile does not have any nails or other securing elements passing directly through the tile but is secured to the 30 roof by means of the metal forming a facing.

In Fig. 9 the roofing tiles are made with a metal face 25, the face having lugs 26 welded thereto, and a plastic composition 27 molded around the lugs and on the back of the metal. 35 A tongue 28 is also preferably molded on the back of the tile, extending through the back-

ing and projecting from one end to allow nailing to a roof structure. In this form of construction the side edges of the metal facing are formed with grooves 29 by having a 40 reverse fold of the metal extending backwardly over the top of the tile and lock two tiles together to form a water tight seal at the joint. A locking strip 30, formed with inturned ends 31, is slipped from the edge 45 over two tiles, the inturned part 31 engaging in the grooves of two adjacent tiles. These strips are substantially the length of the tile and may bend down over the end, the strip and the facing metal projecting beyond the 50 lower end of the tile, as shown in Fig. 6.

Various changes may be made in the principles of my invention without departing from the spirit thereof, as set forth in the description, drawings and claim. 55

I claim:

A tile having a metal face and a composition back, lugs formed of channel-shaped metal secured to the back of the face with one of the flanges of each of the lugs secured to 60 the face, the said lugs being set inwardly from the side edges and corners of the plate, the edges of the plate terminating at substantially the side edges of the composition back, the marginal edges of the metal face merging 65 with the marginal edges of the composition and forming a composite metal and composition marginal edge of the tile.

In testimony whereof I have signed my name to this specification.

ISRAEL EVANS.
